COOLING BED FOR METAL RODS OR BARS.

APPLICATION FILED FEB. 21, 1913.

Patented Feb. 2, 1915.

3 SHEETS-SHEET 3.

UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

COOLING-BED FOR METAL RODS OR BARS.

1,126,978.

Specification of Letters Patent.

Patented Feb. 2, 1915.

Application filed February 21, 1913. Serial No. 749,792.

To all whom it may concern:

Be it known that I, JEROME R. GEORGE, a citizen of the United States, residing at Worcester, in the county of Worcester and 5 Commonwealth of Massachusetts, have invented a new and useful Improvement in Cooling-Beds for Metal Rods or Bars, of which the following is a specification, accompanied by drawings forming a part of 10 the same.

My invention relates to that class of cooling beds in which a metal rod or bar as it is delivered from the rolls of a rolling mill is received upon a series of spaced conveyer 15 rolls having intervening receiving tables, from which the rods are transferred sidewise to that portion of the bed on which the cooling takes place.

The objects of my invention are to provide 20 an improved receiving table to receive the rods from the rolling mill; to provide an improved transferring mechanism for moving the rod sidewise from said receiving table, and also to provide means for the reception 25 of a succeeding rod before the removal of the previous rod from the receiving table.

These objects, among others, I accomplish by means of the construction and arrangement 30 of parts as hereinafter described, the novel features being pointed out in the annexed claims.

Referring to the accompanying drawings, Figure 1 is an end elevation of a cooling bed 35 embodying my invention, shown in sectional view on the plane of the broken line 3—3, Fig. 2. Fig. 2 is a side view of the upper part of my improved conveyer. Fig. 3 is a detached view of the receiving table and 40 transferring mechanism shown in vertical, sectional view on the plane of the broken line 3—3, Fig. 2, with the transferring mechanism in its normal position. Fig. 4 is a similar sectional view, but with the 45 transferring mechanism at the end of its swinging movement after transferring a rod from the receiving table to an adjacent trough. Fig. 5 represents the receiving table in sectional view on the plane of the 50 broken line 5—5, Fig. 2, with a transferring mechanism adapted to receive a second rod from the mill before the first rod has been transferred from the receiving table. Fig. 6 is a similar view to that shown in Fig. 5, but

with the transferring mechanism shown at 55 the end of its operative stroke. Fig. 7 is a vertical, longitudinal, sectional view through the receiving table, on the plane of the broken line 7—7, Fig. 5. Fig. 8 is a vertical, longitudinal, sectional view through 60 the receiving table, on the plane of the broken line 8—8, Fig. 3. Fig. 9 is a longitudinal, horizontal, sectional view on the plane of the broken line 9—9, Fig. 3.

Similar reference letters and figures refer 65 to similar parts in the different views.

Referring to Fig. 1, I have shown such portion of the operating mechanism of a cooling bed as is necessary to illustrate the nature of my present invention, a portion of 70 the supporting framework and unessential parts of the operating mechanism having been omitted for the sake of clearness. In the remaining Figs. 2 to 8, inclusive, I have shown only those portions which are concerned in my present invention in detached views and upon a larger scale.

Referring to Fig. 1 which represents an end view of the cooling bed, 1 denotes a supporting framework, 2 one of a series of 80 inclined notched bars to which an oscillating movement is given by suitable mechanism to transfer the heated rods from the upper to the lower notches by a step-by-step movement, the time required for the sidewise 85 movement of the rods from notch to notch across the bars 2 allowing the rods to cool. The rods are first received from the finishing rolls of the mill by a longitudinal movement over a series of conveyer rolls, one of which 90 is shown at 3, Fig. 1, said rolls 3 having an intervening receiving table 4. Supported upon the conveyer rolls 3 and the intervening receiving table 4 the rods occupy the position indicated at 5, Fig. 1. From the position shown at 5 the rods are moved onto an inclined table 6, terminating at its lower edge in a trough 7 into which the rods slide by gravity. The rods are moved from the receiving table 4 by a swinging plate 8 attached to arms 9, which are carried upon a rock shaft 10 operated by the attendant through a lever handle 11.

The receiving table 4 is shown in longitudinal sectional view in Figs. 7 and 8, upon 105 which the heated rods are received in the direction of the arrows *a*. The receiving table 4 is provided with a series of raised

portions 12, having their upper surfaces slightly below the supporting surfaces of the conveyer rolls 3 and arranged to support the weight of the heated rods between said conveyer rolls in a plane above the lower ends or tips 13 of the swinging plate 8. The sides of the raised portions 12 opposed to the longitudinal movement of the rod are beveled, as shown at 14, to conduct the advancing end of the rod over the raised portions 12. The swinging plate 8 is provided with forwardly extended portions 15 having their sides opposing the longitudinal movement of the rod beveled, as shown at 16, Fig. 8, to facilitate the movement of the rod past the forwardly extended portions 15. The swinging plate 8 and the receiving table 4 do not present any obstruction to the longitudinal movement of the rod in the direction of the arrows *a*. The inclined table 6 is provided with transverse slits or openings 17 to provide for the swinging movement of wings 18, Fig. 1, attached to the notched bars 2, for the purpose of lifting the rods out of the trough 7, the construction and operation of said notched bars 2 and wings 18 being substantially like that shown in the United States Patent to Victor E. Edwards, No. 701,024 issued May 27, 1902.

When a heated rod has been received from the rolling mill upon the conveyer rolls 3 and receiving table 4, it sometimes occurs that the advancing end of the next succeeding rod from the mill is projected upon the cooling bed before the mechanism for transferring the first rod from the receiving table has returned to its normal position. In order to prevent the overlapping rods from colliding I use a transferring mechanism in the first two sections of the cooling bed, as represented at the right hand end of Fig. 2, and in larger and sectional views in Figs. 5, 6 and 7. The swinging plate which is used in the remaining sections of the cooling bed and is shown on an enlarged scale in Figs. 3, 4, 8 and 9 is connected to a different form of swinging plate used in said transferred mechanism. Said swinging plate consists of a pusher plate 19, having at its upper edge a curved platform 20 concentric with the axis of the shaft 10 about which the pusher plate swings. The curved platform 20 is reduced in height with its receiving end bent downward at 21, Fig. 7, in order to enable the succeeding rod as it leaves the first conveyer roll 3 to be received upon the platform 20 instead of the receiving table 4, provided the pusher plate 19 has been advanced sufficiently to bring the platform over the receiving table 4, or in the position shown in sectional view in Fig. 6.

Supported by the rigid framework of the cooling bed above the receiving table 4 and

also above the curved platform 20, when in its advanced position, as shown in Fig. 6, I provide a housing 22 consisting of an inverted trough open at the bottom, beneath which the succeeding rod is projected and caught upon the curved platform 20 in the position shown at 23, Fig. 6.

If the pusher plate 19 and platform 20 swing back into the position shown in Fig. 5, the rod 23 falls and is caught upon the conveyer rolls 3 and receiving table 4 in the position shown at 24, Fig. 5, the side 25 of the trough shaped housing 22 serving to scrape the rod from the platform 20 as it swings backward.

The receiving table 4 and the curved platform 20, when the latter has been advanced in the position shown in Fig. 6, form an upper and lower deck, the lower deck or table 4 receiving the rod from the mill when the transferring mechanism has been swung back into its normal position, and the upper deck or platform 20 receiving the rod when the transferring mechanism has been swung forward, as shown in Fig. 6.

The overlapping of the rods from the mill will be confined usually to the first two sections of the cooling bed. Throughout the remaining sections of the cooling bed the platform 20 is not required and the transferring mechanism consists of the swinging plate 8 carried upon arms 9 attached to the rocking shaft 10. The pusher plate 19 at the front edge of the platform 20 is constructed like the swinging plate 8, that is, it has forwardly extended portions 26 corresponding with the portions 15 on the swinging plate 8 and having the sides opposing the advancing end of the rod beveled as at 27. The receiving table 4 and also the supporting surface of the conveyer rolls 3 are inclined toward the swinging plate 8 and the pusher plate 19 so that the rod projected over these surfaces tends to slide toward the inner ends of the rolls and the rod is held in contact with the transferring mechanism, as shown at 24, Fig. 5, and 26, Fig. 3. In this position the advancing end of the rod is moved over the raised portions 12 of the receiving table and also in contact with the forwardly extended portions 15 of the swinging plates 8 and the forwardly extended portions 26 of the pusher plate 19. The advancing end of the rod is thereby prevented from striking any projecting shoulder of the cooling bed or being caught between the receiving table and the transferring mechanism.

When the heated metal transferred to the cooling bed consists of thin strips of the character of band iron, for example, it is important that means be provided to prevent the advancing end, even when bent or deflected from a straight line, from being

presented to a crack or opening, however slight, between the receiving table and the pusher plate. The space between the receiving table and the edge of the pusher plate must be of sufficient size to allow ample clearance when the parts have been expanded by heat and, in order to remove any possibility of the advancing end of the rod from being caught in the open space, 5 the lower edge of the pusher plate extends below the supporting surface of the receiving table; the forwardly projecting portions 10 of the pusher plate alternate with the raised portions 12 of the receiving table; 15 and the forwardly projecting portions 15 overlap the beveled surfaces 14 of the receiving table. By means of the above construction, the beveled surfaces 13 and 14 move the advancing end of the heated metal 20 away from the open spaces between the receiving table and the pusher plate.

I claim,

1. In an apparatus of the kind described, a receiving table for the reception of a rod 25 provided with a series of raised portions upon which the rod is supported, and a swinging plate having its lower edge conforming to the surface of said receiving table.

2. In an apparatus of the kind described, a receiving table having its upper surface at different vertical heights to provide spaced supports for a rod, and a movable plate for transferring a rod from said receiving table, having its lower edge extending 30 below the plane of said rod supports.

3. In an apparatus of the kind described, a receiving table, and a plate movable transversely across said table, having a series of 40 forwardly extended portions to provide spaced contact surfaces for pushing a rod sidewise.

4. In an apparatus of the kind described, means for supporting a rod, and means for 45 transferring the rod by a sidewise movement from said rod support, comprising a plate movable transversely across said rod support, having portions extending forwardly to form spaced contacting surfaces for the 50 rod.

5. In an apparatus of the kind described, a receiving table having raised portions to provide spaced supports for a rod, and a plate at an angle to the supporting surface 55 of the receiving table movable transversely across the table for transferring a rod therefrom by a sidewise movement, said plate having forwardly extended portions alternating with the rod supporting portions of 60 said receiving table.

6. In an apparatus of the kind described, means for supporting a rod, and means for transferring a rod therefrom by a sidewise movement, comprising a plate movable 65 transversely to said rod support, said plate

having forwardly projecting portions to contact with the rod, each of said portions presenting a beveled surface to the advancing end of a rod.

7. In an apparatus of the kind described, 70 means for supporting a rod, means for pushing a rod by a sidewise movement from said rod support, means for supporting a rod in a plane above the plane of said first rod support, and means for transferring a 75 rod from said higher to said lower rod support.

8. In an apparatus of the kind described, a receiving table, a plate movable transversely across said receiving table, and a 80 platform carried by said plate adapted to be moved over said receiving table by the forward movement of said movable plate.

9. In an apparatus of the kind described, 85 means for supporting a rod, and means for supporting a second rod above said first supporting means, said second supporting means being movable to effect the removal of both of said rods from their respective supporting means.

10. In an apparatus of the kind described, a rod support, a plate capable of swinging about an axis above said support and transversely across said support, and a platform curved concentrically with the 95 axis of said swinging plate, and adapted to be moved over said rod support as said plate moves to transfer a rod from said rod support, and means for conducting a rod from the plane of said rod support to the 100 plane of said platform.

11. In an apparatus of the kind described, a support for a rod, a platform movable into a position over said rod support, and means for removing a rod from said platform upon 105 its reverse motion.

12. In an apparatus of the kind described, a receiving table, a plate capable of swinging transversely across said table to remove a rod therefrom by a sidewise movement, a 110 platform having its upper surface curved concentrically with the axis of said swinging plate, and means for transferring a rod from said platform during its swinging movement.

13. In an apparatus of the kind described, a rod support movable transversely to the axis of the rod, and a fixed housing covering said rod support and open at the bottom.

14. In an apparatus of the kind described, 120 an inverted trough shaped housing adapted to receive a rod from a rolling mill, and a rod support beneath said inverted trough, movable transversely thereto.

15. In an apparatus of the kind described, 125 a receiving table having raised portions forming spaced supports for the rod, said raised portions presenting beveled surfaces to the advancing end of the rod, a pusher plate movable transversely to said receiving 130

- table and having projecting portions to contact with the rod, alternating with the raised portions of said receiving table and overlapping the beveled surfaces on the table.
- 5 16. In an apparatus of the kind described, a receiving table having raised portions to form spaced supports for a rod, a pusher plate having projecting portions to contact with the rod presenting beveled surfaces to 10 the advancing end of the rod, said projecting portions with their beveled surfaces extending below the plane of the rod supporting surfaces of said receiving table.
- 15 17. In an apparatus of the kind described, a receiving table having raised portions presenting beveled surfaces to the advancing end of a rod by which said rod is conducted upon said raised portions, a pusher plate having projecting portions to contact with 20 a rod presenting beveled surfaces to conduct the rod over said projecting portions, with the lower edges of said projecting portions and the lower edges of said beveled surfaces extending below the plane of the rod supporting surfaces of said receiving table.
- 25 18. In an apparatus of the kind described, a receiving table having raised portions presenting beveled surfaces to the advancing end of a rod, and a pusher plate having forwardly projecting portions overlapping the beveled surfaces of the receiving table.
- 30 19. In an apparatus of the kind described, means for successively advancing rods, a table for receiving one of said rods, and 35 means for interposing a support beneath a following rod, said means adapted to remove the first rod from said receiving table.
- 35 20. In an apparatus of the kind described, means for successively advancing rods, a 40 table for receiving one of said rods, and means for interposing a support in the path of a following rod in a different plane from the plane of said receiving table, said means

adapted to remove the first rod from said receiving table.

21. In an apparatus of the kind described, a receiving table for a rod, means movable in one direction to remove said rod from said table, said means forming a support for a second rod, and means cooperating with said first mentioned means in its movement in another direction to effect the removal of said second rod therefrom.

22. In an apparatus of the kind described, means for supporting a rod, supporting means for a second rod adapted to be moved over said first supporting means, and means cooperating with said second supporting means for transferring a rod therefrom to said first supporting means.

23. In an apparatus of the kind described, a receiving table, means for advancing a rod onto said receiving table, means for removing said rod from said table, and means rendered operative by the movement of said removing means for depositing a second rod on said table.

24. In an apparatus of the kind described, means for successively advancing a plurality of rods, a receiving table for said rods, and 70 means, adapted to be interposed in the path of said rods for constraining movement thereof into a plane above the plane of said receiving table.

25. In an apparatus of the kind described, 75 a receiving table for rods, means for removing a rod from said table, said means forming a support for a second rod, and means cooperating with said removing means to effect the deposit of said second rod on said 80 table.

Dated this 12th day of February 1913.
JEROME R. GEORGE.
